UNITED STATES PATENT OFFICE.

ANDERS LASSEN BERTHELSSEN, OF CHICAGO, ILLINOIS.

FABRIC-CUTTING DEVICE.

1,399,924.

Specification of Letters Patent. Patented Dec. 13, 1921.

Application filed April 19, 1920. Serial No. 374,975.

To all whom it may concern:

Be it known that I, ANDERS LASSEN BERTHELSSEN, a subject of the King of Denmark, residing at Chicago, in the county of Cook and State of Illinois, have invented certain new and useful Improvements in Fabric-Cutting Devices, of which the following is a specification.

The present invention appertains to that type of fabric cutting device disclosed in my previous Patent No. 1,318,346, granted October 14, 1919, the objects of these improvements being in part to simplify the construction without reducing its effectiveness, and in part to produce such a construction wherein the operative point of the edge of the cutter is readily controllable in a simple manner.

Other objects and advantages will more fully appear as the description proceeds, the novel features thereof being pointed out in the appended claims.

For a full understanding of the invention reference is to be had to the following description and accompanying drawings, in which:

Figure 1 is a side elevation of a device constructed in accordance with my present invention;

Fig. 2 is a bottom plan view;
Fig. 3 is a top plan view;

Fig. 4 is a view with the side of the body broken away and parts shown in section to show more clearly the details of construction, especially with reference to the mounting of the cutting blade;

Fig. 5 is a longitudinal sectional view on the line 5—5 of Fig. 4;

Fig. 6 is an end elevation;

Figs. 7 and 8 are sectional views on the lines 7—7 and 8—8, respectively, of Fig. 1;

Fig. 9 is a side elevation of a modified form of my invention;

Fig. 10 is a vertical longitudinal sectional view thereof;

Fig. 11 is a horizontal sectional view on the line 11—11 of Fig. 10;

Fig. 12 is a detail view of the blade holder portion of this modified construction in open position to free the blades; and

Figs. 13 and 14 are sectional views on the lines 13—13 and 14—14 respectively, of Fig. 9.

Throughout the following detail description and on the several figures of the draw-

ings, similar parts are referred to by like reference characters.

Specifically describing the invention and referring to that form of the device disclosed in Figs. 1 to 8, 1 designates the body portion thereof which is tubular in form, in cross section oval-shaped. In the manufacture of the article this part 1 may either be constructed from a solid tubular piece, or, as may be preferred from two pieces, the edges of which are suitably welded together. Disregarding this phase as immaterial, the tubular piece is split longitudinally and transversely of its narrow dimension for a distance substantially one-half its length, and at the bottom the two sides are then placed firmly together so as to form a blade holder 2. This leaves the upper portion at the split end arched over the blade holder with the edges 3' spaced equally from the blade holder and depending slightly below the plane of the top of the holder. The forward extremity of this arched portion is cut shorter than the blade holder and along a curved line extending diagonally of the said holder as indicated at 4, the function of which part is to provide a cloth guide or guiding means as well as a protector for the blade. This part, however, will be hereinafter referred to as a guiding means or guide under the designation of the numeral 3. Between the pressed sides of the holder 2 a cutting blade 5 is adapted to be inserted and held, the blade being provided preferably with a notch 5' at either end engageable with a protuberance 6 formed by stamping or punching in the metal at the forward end of the holder. A similar protuberance 7 is provided at the opposite end of the pressed portion so as to hold the blade with the end notch engaging with the forward protuberance 6, as clearly shown in full lines in Fig. 4 of the drawings. Before leaving this portion of the device, it should be noted particularly that the construction in the manner specified leaves the forward extremity of the pressed portion projecting substantially beyond the end of the guide 3, thus constituting a support for the cloth as it passes into the mouth of the guide 3, an important feature of construction of the device.

Upon this body portion 1 of the cutter is slidably mounted a split sleeve 8 and herein lies the main feature of construction of

my device because this element functions in many ways to control the operation or action of the instrument. As will be observed the sleeve conforms in general to the contour of the tubular member 1, and being of material preferably possessing resiliency sufficient tension is maintained to insure that the sleeve will retain its adjustment position at any point within the range of its adjustment. Being split longitudinally along the line 9 (see Fig. 3) it is readily slidable upon the body from one end and at its lower forward end the sleeve is pinched together, as at 10, so as to frictionally grip the blade holder 2.

It will be apparent from the foregoing description that this formation of the sleeve tends to hold the blade holder 2 centrally aligned with respect to the over-hanging guide 3, prevents the displacement of the blade 5 from between the sides of the holder ends until removed from the body and limits the longitudinal movement of the sleeve in one direction by reason of the co-operation with the shoulder of the part 1 produced by the pressing together of the sides to form the holder 2. The main function for the sleeve, however, is to regulate the severing or cutting point of the edge of the blade 30 and this will be clear from the explanation of the use or operation of the device.

In the use of the device the cutting operation is accomplished by either a relative movement of the cutter with respect to the cloth, or of the cloth with respect to the cutter, depending upon whether the material is held stationary or the cutter so held during the cutting operation. The line of cut of the cloth is first determined, this being 40 preferably at right angles to the selvage edge of said material which passes over the projecting extremity of the blade holder 2 until it meets with the extremity of the guide 3. The curving or inclined edge 45 first acts to fold the material and then directs the same at an angle to the blade projecting slightly above the holder 2, thus cutting the material as the edges thereof are guided laterally or outwardly by coming into contact with the pinched portion 10 of the sleeve lying below the guide 3. Obviously then, as the cutting point of the edge of the blade becomes dull from use the sleeve 55 may be moved along the body 1 from the dotted line position of Fig. 1 toward the full line position, in this way prolonging the serviceability of the blade to the maximum extent. It should be understood, of course, that the blade may also be reversed end for 60 end if desired, or if possessing a double cutting edge the blade may be reversed edge for edge. To reverse or displace the blade, it is only necessary to slide the sleeve off the body and by springing open slightly the 65 sides of the holder 2 the blade will fall out.

By pressing the metal of the body together at its end and cutting an opening 11 provision is made for hanging the cutter at a convenient position for access, but the device is designed to be made of pocket size so as to 70 be conveniently carried and ready for use when desired, the cutting element being always completely protected by the guide 3 which surrounds the same.

Passing now to the modified form of the 75 device shown in Figs. 9 to 14, it will be observed that this possesses the general features of the construction of the previous form hereinbefore defined. In this modification, however, the body consists of a sectional blade holder 12 composed of complementary sections 12', 12" pivoted together at their forward extremities as at 13. Provision is made for holding two cutting blades 14, 14, one of which of course is in 80 inoperative position normally but subject to interchange with the other. By cutting out the material of the holder, a yieldable projection or arm 15, is formed, speaking of the sections of the holder as a unit. The 85 holder is pivotally connected to the overhanging guide or protector member 16, the equivalent of the member 3 in the preferred form, the pivot for the parts being designated 17. In closing these parts together 90 the guide comes into contact with the projection 15 which resists the full closing action. Upon the holder and guide unit, the sleeve 8^a, similar to the sleeve 8, is slid from the forward end, a sufficient frictional resistance being thus produced to hold the sleeve at any adjusted position. To enable an adjusted position to be positively retained I preferably notch the lower edge of the holder 12 as at 18 and turn up a lip 19 100 at the lower part of the mouth of the sleeve to engage in the notches. By pressing together the forward end of the guide 16 and holder 12 at the points indicated by arrows *x*, *x*, Fig. 9, the lip may be disengaged from 105 the notches and slid along in either direction for the purposes hereinbefore specifically mentioned in reference to the preferred form. The cutting edge of the blade 14 in this form, which is in operative position, 110 may be shifted by moving the sleeve 8^a in a longitudinal direction as above described with reference to the preferred form.

When it is necessary to insert a new cutting blade, the sleeve 8^a may be entirely removed in a forward direction, thereby releasing the holder and springing open slightly the sides of said holder whereupon the blade or blades will fall out.

Protuberances 20, 20, are punched in the 125 sections of the holder 12 so as to co-operate with the sides of the guide 16 to hold the blade centrally with respect to said guide.

The sleeve 8^a is pressed together along its lower portion at opposite sides so as to form 130

shoulders 21 which closely grip the blade holder and which shoulders as in the preferred form constitute guiding or gripping means for the cloth in the cutting operation so that the sleeve functions in substantially the same manner in this modification as in the preferred form mentioned.

Thus the invention is subject to this and such other modifications within the purview 10 of the invention without in any way departing from the spirit thereof and within the scope of the appended claims.

Having thus described my invention, what I claim as new and desire to secure by Letters Patent is:

1. A fabric cutting device of the class described, comprising a blade holder, and means movable along the holder to thereby change the point of the blade edge which is 20 operative to effect the cutting action, said means being constructed to guide the severed portions of the material laterally outward with respect to the blade edge.

2. A fabric cutter comprising a blade holder and a sleeve slidably mounted directly upon the holder and shiftable longitudinally there-along to different positions of adjustment to control cutting action.

3. A fabric cutter comprising a body constituting a manipulating means and formed 30 with a blade holding portion adapted to receive a cutting blade and a sleeve slidably mounted directly upon the body and movable there-along into coöperative relation 35 with respect to the blade holding portion to determine the point of the blade edge which is operative for cutting.

4. A fabric cutter comprising a body constituting manipulating means and formed 40 with a blade holding portion at one end and as a part thereof with cloth guiding means associated with said blade holding portion for preliminarily folding the fabric over the holder and thereafter directing the fabric at 45 an angle against the edge of the blade, and separate means adjustably mounted on the body for directing the edges of the cloth away laterally of the holder.

5. A fabric cutter of the class described 50 comprising a blade holder adapted to receive a blade between its sides, and a sleeve mounted upon said holder and constituting retaining means for preventing displacement of the blade, and controlling the point 55 of cutting action of the edge of said blade.

6. A fabric cutter of the class described

comprising a blade holder adapted to receive a blade between its sides, and a sleeve mounted upon said holder and constituting retaining means for preventing displacement of the blade, and controlling the point of cutting action of the edge of said blade, 60 said sleeve being adjustable with reference to the blade in a longitudinal direction.

7. A fabric cutter of the class described 65 comprising a body portion formed with a blade holder and a guide means overhanging said holder and a blade adapted to be mounted therein, and a split sleeve mounted upon the body and conforming to the contour thereof with respect to the blade holder and guiding means, said sleeve preventing displacement of the blade and constituting guiding means for the fabric.

8. A fabric cutter of the class described 70 comprising a tubular body, said body being split longitudinally from one end and the sides thereof at the split portion pressed together to form a blade holder and a sleeve mounted upon said body and having a portion thereof pressed together to grip the blade holder and maintain the same centrally alined with respect to the body during the cutting action.

9. A fabric cutter of the class described, 75 comprising a tubular body having the sides thereof at one end and along its lower portion pressed together to form a blade holder, the sides thereof adjacent the blade holder overhanging the same and constituting a 80 blade protector, and a sleeve mounted upon the body, and operable over the blade protector, said sleeve being pressed together at 85 its lower portion to grip the blade holder, thereby forming cloth guiding shoulders 90 constituting means for limiting movement of the sleeve in one direction.

10. A fabric cutter comprising an elongated body having separable side members forming a blade holder between which a cutting blade is adapted to be inserted, means on said blade holder with which the blade is engaged to hold it in position between the sides, a protector over-hanging the blade holder and blade, and a sleeve mounted for 100 movement along the body and engaging beneath the blade holder to prevent displacement of the blade from between the sides and maintain the blade holder centrally alined with respect to the protector.

In testimony whereof I affix my signature.
ANDERS LASSEN BERTHELSEN.
